UNITED STATES PATENT OFFICE.

RENÉ MAROT, OF PARIS, FRANCE.

APPARATUS FOR PREPARING A MIXTURE OF AIR AND SULFUR DIOXID.

1,024,798.

Specification of Letters Patent. Patented Apr. 30, 1912.

Application filed December 29, 1910. Serial No. 589,854.

To all whom it may concern:

Be it known that I, RENÉ MAROT, citizen of the Republic of France, and resident of 53 Rue de Chateaudin, Paris, in the said Republic, engineer, have invented new and useful Improvements in Apparatus for Preparing a Mixture of Air and Sulfur Dioxid, of which the following is a specification.

This invention relates to improvements 10 in apparatus for preparing a mixture of air and sulfur dioxid having disinfecting properties and capable also of extinguishing conflagrations and for distributing said mixture as soon as produced in the places where it 15 is to perform its action. Previously the movable parts of apparatus of this kind were actuated by an oil or spirit motor and the exhaust of said motor as well as the water which had been employed for refrigerating the cylinder were utilized to heat 20 the mixture of air and sulfur dioxid in order to counteract the cold produced by the vaporization and the expansion of the liquid sulfur dioxid employed as raw material.

This invention consists in a tubular device 25 for the expansion of sulfur dioxid, which in order to counteract the cold produced by the expansion of the dioxid is heated by the exhaust steam, and which 30 allows of the use of a steam engine for actuating the movable parts of the apparatus as well as of the use of the exhaust steam of said motor as a source of heat for the heating purposes as aforesaid.

Figure 1 of the accompanying drawings 35 is a vertical longitudinal section, Fig. 2 a side elevation and Fig. 3 a plan of an expanding device according to the present invention. Fig. 4 is a longitudinal elevation 40 and Fig. 5 a top view of an apparatus for producing and distributing the mixture of air and sulfur dioxid provided with said expanding device.

The expanding device consists in a box 45 *a* of sheet metal having a part *b* in which are arranged series of horizontal tubes *c* whose diameter increases from the lower part upward and are assembled by means of bent tubes *c'* (these tubes being fixed by 50 means of removable bushings) in order to provide a number of coils of gradually increasing cross section equal to that of the bottles containing the liquid sulfur dioxid for feeding the apparatus. The lower end 55 of each coil is connected to the respective bottle of sulfur dioxid *n*, while its upper

extremity is connected to a free space *d* which is formed in the upper part of the box *a* and does not communicate with the room *b* in which the coils are arranged. 60

The steam designed for heating purposes is admitted in said space *b* through an upper inlet pipe *e* and owing to its contact with the coils the sulfur dioxid absorbs heat therefrom and when it reaches the space *d* 65 is entirely vaporized and expanded. As a preventive means however, in case some small liquid drops should remain in the mixture, there is provided a wall *f* against which the sulfur dioxid impinges and which 70 constitutes a baffling device over which the sulfur dioxid is made to pass in order to escape through the outlet *g*; the upper part of the wall *f* is provided with a sloping portion *f'* designed to give greater security 75 against the passage of liquid. In the top of the space *d* is provided an air inlet *h* so that it is a mixture of air and expanded sulfur dioxid which escapes through the outlet *g*. On one side of space *d* is provided an opening *i* normally closed by a sliding door 80 through which the action of the apparatus can be viewed.

As will be seen in Figs. 4 and 5, the tubular expanding device above described 85 is connected with the bottles *n*, *n'* containing the liquid sulfur dioxid, these bottles being preferably placed upon a weighing apparatus *o* in order to permit the operator to observe at all times the quantity of 90 sulfur dioxid still remaining; the gaseous mixture of air and sulfur dioxid as it escapes from space *d* flows in a known manner in a pipe *j* which contains electrodes *k* connected with a dynamo *l* in order to produce 95 electric sparks in the body of the gaseous mixture. The dynamo *l* is actuated by means of a driving belt through the shaft of a fan *m* which in its turn is actuated in the same manner by the prime mover. 100

I claim:—

A device for expanding sulfur dioxid and thoroughly mixing the latter with air, comprising: a box; series of tubes in said box, the diameter of which increases from bottom to top; bent tubes connecting said tubes together in each vertical row; a connection piece on the lowest tube in each vertical row, for connecting it to a bottle containing liquid sulfur dioxid; a steam inlet aperture in the wall of said box; a chamber at the upper part of said box, connected with each 105 110

vertical row of tubes; a partition in said chamber to act as a baffle; an inclined portion at the upper edge of said partition; an air inlet aperture in the wall of said chamber; a lateral aperture in the wall of the latter for the discharge of the mixture of expanded sulfur dioxid and air.

5 In testimony, that I claim the foregoing

as my invention, I have signed my name in presence of two witnesses, this 16th day of 10 December, 1910.

RENÉ MAROT.
